UNITED STATES PATENT OFFICE.

LEOPOLD ALMQUIST, OF NEW YORK, N. Y., AND VICTOR WILLOUGHBY, OF RIDGEWOOD, NEW JERSEY, ASSIGNEES TO AMERICAN CAR AND FOUNDRY COMPANY, OF NEW YORK, N. Y., A CORPORATION OF NEW JERSEY.

DRAIN TRAP.

Application filed April 28, 1926. Serial No. 105,187.

Reference is had to the accompanying drawings which illustrate the preferred form of the invention; though it is to be understood that the invention is not limited to the exact details of construction shown and described, as it is obvious that various modifications thereof within the scope of the claims will occur to persons skilled in the art.

In said drawings:

10 Figure 1 is a sectional elevational view of a portion of a refrigerator car with a trap therein formed in accordance with our invention;

15 Fig. 2 is a plan view of the trap shown in Fig. 1;

Fig. 3 is an enlarged view of the hinge connection shown in Fig. 1;

Fig. 4 is a plan view of a modified hinge structure;

20 Fig. 5 is a sectional elevational view of a portion of a refrigerator car with a modified trap therein;

Fig. 6 is a plan view of the trap shown in Fig. 5;

25 Fig. 7 is a sectional view illustrating the connection of the hinge member to the cap, and

Fig. 8 is an elevational view of a modified hinge.

30 Our invention relates to drain traps suitable especially for refrigerator cars, for sealing their drainage outlets against entrance of outside air. We aim to provide a simple, rugged and durable device, easy and economical to manufacture and install. In particular, we aim to assure proper opening of a movable cap of such a trap in cleaning, and to obviate injury to the cap; to provide for the normal support of such cap on the outlet 35 of the trap when lowered; and to provide against the cap being raised too far (past "dead center"), so as to remain open automatically instead of automatically closing.

40 Referring to Figs. 1, 2 and 3 of the drawings, and particularly to Fig. 1, a refrigerator car is illustrated having a sill 1 with an angle 2 secured thereto by rivets. A beam 3, which rests upon the angle 2, is secured to the sill 1 by means of bolts 4. The flooring of the car 45 comprises a sub-floor 5 of wood which con-

ncts directly with the beam 3. Above the sub-floor are placed a layer of cork 6, a layer of suitable weather-proofing compound 7, a layer of cellular heat insulating material 8, and a layer of water-proof felt 9. The ice 55 pan 10 of the refrigerator car is positioned upon the layer of water-proof felt as illustrated in Fig. 1. The sides of the car comprise an outer sheathing 11 of wood and an inner wooden sheathing 19 between which 60 are placed various layers of heat insulating material.

The ice pan 10 has an opening 26 formed therein to accommodate a bowl 27. The bowl 27 is provided with a flange 28 which is secured to the ice pan by means of rivets 29. An opening in the bottom of the bowl 27 is provided for receiving an outlet pipe 30. A suitable flange 31 is formed on the bowl for engaging the outlet pipe. The outlet pipe 70 extends into the bowl to a distance somewhat below the top of the bowl and the flange 28. A cap 32, which is hinged to the top of the bowl, is provided for covering the top of the outlet pipe 30 and for forming a water seal 75 with the outlet pipe in the bowl.

The cap 32 comprises a flat top portion 33 and a flaring flange 34 extending downwardly from the flat portion 33. A rib 35 is pressed in the top part 33 and the flange 34 as shown 80 in Figs. 1 and 2. The bottom portion 36 of the rib 35 rests upon the top of the outlet pipe 30 when the cap is lowered in position. A sloping end surface 37 is formed on the rib 85 in order to assure proper opening of the cap and prevent the breaking of the hinge connection between the cap and the bowl when a swabbing tool is forced through the outlet pipe. A plate 38, which is secured to the top 90 of the cap by rivets 39, is provided with three fingers 40, 41 and 43. The end portions 49 and 50 of the fingers 40 and 41 on the plate 38 are turned over to form a portion of a hinge. The central finger 43 serves to engage a plate 51 for limiting the raising of the cap 32. The plate 51 is secured to the ice pan 10 and the flange 28 of the bowl by means of two of the rivets 29, as illustrated in Fig. 2 of the drawings. Plate 51 is provided with a central finger 53 having the end thereof turned over 100

to form a hinge with the fingers 40 and 41 of the plate 38 on the cap. A suitable cotter pin 54 projects through the turned-over end portions of the fingers 40 and 41 on the plate 38 and the finger 53 on the plate 51. The central finger 43 on the plate 38 engages the top of the plate 51 when the cap is raised to its extreme position. The extreme raised position of the cap is indicated by dot and dash lines in Fig. 1 of the drawing. Fig. 3 of the drawing also shows the hinge in its extreme open position. The center of mass of the cap is substantially located at a point indicated by the reference character 55. Such center of mass does not pass over the hinge so that the force of gravity always exerts a force tending to lower the cap when it is in raised position. When the cap is in its extreme raised position, as indicated by the dot and dash lines in Fig. 1 of the drawings, the point indicating the center of mass is shown to the right of the hinge connection between the cap and the bowl and accordingly a force is exerted tending to lower the cap.

25. The bottom surface 36 of the rib 35 supports the cap when it is in lowered position. The inclined surface 37 of the rib serves as a means for engaging a swabbing tool when the outlet pipe is being cleaned. The inclined surface guides the swabbing instrument beyond the cap and prevents such instrument from becoming engaged with the flange on the cap. Moreover the rib 35 serves to strengthen the cap.

35. In Fig. 4 of the drawings a modified hinge structure is shown for connecting the cap 32 to the bowl 27. In the hinge structure shown in Figs. 1, 2 and 3 of the drawings, the turned-over end portion of the finger 53 on the plate 51 is positioned between the turned-over end portions of the fingers 40 and 41 on the plate 38. In the hinged structure shown in Fig. 4 the position of the fingers with respect to each other is reversed.

45. A plate 56 is secured to the cap 32 by rivets and is provided with a central finger 57 having a turned-over end portion. A hinged plate 58 is secured to the flange 28 on the bowl by means of two of the rivets 29. Such hinge plate 58 is provided with two fingers 59 and 60 having turned-over end portions which are disposed on opposite sides of the finger 57 on the hinge plate 56. Projecting fingers 61 and 62 on the plate 56 engage the plate 58 to limit the raising of the cap. Referring to Fig. 1 of the drawings it may be noted the cap 32 is hinged to the plate on the bowl at a point below the top surface of the cap and above the top of the bowl.

60. In the modification shown in Figs. 5, 6 and 7 of the drawings, corresponding parts will be indicated by like reference characters. The bowl, the outlet pipe and the rib structure on the cap in the trap shown in Figs. 5, 6 and 7 are exactly similar to the same parts

shown in Figs. 1, 2 and 3 of the drawings. The hinge connection between the cap and the flanges on the bowl has been changed and the position of the cap has been lowered. Upon the flange 34 of the cap 32 a bracket 64 is secured to form a portion of a hinge connection. Such bracket 64 is riveted and welded to the flange 34 on the cap 32 as indicated in Fig. 7 of the drawings. A plate 65, which is secured to the ice pan and the bowl by means of rivets 66, has a downwardly extending portion 67 as indicated in Fig. 5 of the drawings. Such downwardly extending portion 67 has a turned-over end part which encircles the bracket 64, as shown in Figs. 5 and 6 of the drawings. In the modification under consideration the raising of the cap is limited by the flange 34 thereof engaging the plate 65. The extreme raised position of the cap is indicated by dot and dash lines in Fig. 5 of the drawings. The center of mass of such cap is indicated by the reference character 55 used in Fig. 1 of the drawings to indicate the center of mass. It will be noted the center of mass indicated by the reference character 55 is to the right of the pivotal point for the cap, as indicated in Fig. 5 of the drawings. Attention is also called to the fact that the modification shown in Figs. 5, 6 and 7 is provided with a cap having the top thereof level with the floor of the ice pan, and a hinge located within the bowl 27.

In the modification shown in Fig. 8 of the drawings the bracket 64 on the flange 34 of the cap 32 engages a hinge plate 69 which is different from the hinge plate 65 shown in Figs. 5 and 6 of the drawings. The hinge plate 69 which is suitably riveted to the bowl 27 has a downwardly and outwardly extending portion 70 thereon. The portion 70 has a turned-over end part 71 for engaging the bracket 64 on the cap. In Fig. 8 of the drawings the cap is shown in its extreme raised position in order to illustrate the manner in which the flange 34 of the cap engages the plate 69.

What is claimed is:

1. In a trap, a bowl adapted to extend over a floor, an outlet projecting into the bowl and extending nearly to its top, a swingable cap for said outlet having an angular stop rib therein to rest on said outlet, and a hinge connecting the cap with said bowl having its pintle below the plane of the top of the cap and above the floor the angular stop-rib being disposed in the path of a swab inserted in the drain pipe and serving to deflect such swab away from the cap.
2. A closure for drain pipes of refrigerator cars, a cap, means for pivotally mounting the cap to normally overlie and seal one end of the drain pipe and permitting the cap to be swung to a position to one side of the drain pipe upon engagement thereof by

a drain pipe cleaning element, and a cleaning element deflecting member carried by the cap and extending at an oblique angle with respect to the horizontal so that upon engagement of the latter by the cleaning element such cleaning element will be deflected beyond such cap.

3. A hinged, swingable sheet metal trap cap having a flat top, a depending flange, 10 and a stop rib pressed into the cap from the metal of its top and flange portions, and having an oblique inner end.

4. A hinged, swingable sheet metal trap cap having a flat top portion, a depending 15 flange, and a stop rib pressed into the cap from the metal of its top and flange portions, with its inner end sloping upward toward the hinge.

5. In a trap, a bowl with a supporting 20 flange, an outlet projecting into said bowl and terminating below the top thereof, a swingable sheet metal cap having a depending flange surrounding the top of the outlet, a hinge connection between the cap and 25 said supporting flange, and a stop rib pressed into the cap from the metal of its top and flange portions to rest on said outlet, the inner end of said rib sloping toward said hinge.

6. In a trap having a bowl and an outlet 30 projected thereinto, a cap comprising a hingedly mounted inverted cup-shaped element positioned over said outlet and having an inwardly extending rib formed therein defining a seat adapted to rest upon the outlet 35 to support said cap and an upwardly extending deflecting portion.

7. In a trap, a bowl having an outlet projecting thereinto, a pivotally mounted cap 40 normally arranged over the outlet and provided with an internal stop rib defining a support for the cap adapted to rest on the outlet and an internal deflector for engagement by a cleaning tool.

In witness whereof we have hereunto set 45 our hands.

LEOPOLD ALMQUIST.
VICTOR WILLOUGHBY.
